UNITED STATES PATENT OFFICE.

GEORGE T. PEARSONS, OF NEW YORK, N. Y.

FIRE EXTINGUISHER.

1,403,191.

Specification of Letters Patent. Patented Jan. 10, 1922.

Application filed April 2, 1920. Serial No. 370,904.

To all whom it may concern:

Be it known that I, GEORGE T. PEARSONS, a citizen of the United States, residing in the borough of Manhattan, city, county, and 5 State of New York, have invented new and useful Improvements in Fire Extinguishers, of which the following is a specification.

This invention relates to fire extinguishers of the type in which a fire extinguishing 10 liquid is ejected from a reservoir by pressure created within the reservoir, such as a gas pressure resulting from the reaction of the mixing of gas generating materials normally maintained in a separated condition in 15 a generator, and relates particularly to extinguishers of this type adapted as unit sprinklers in which means are retained in position to hold the gas generating materials in a separated condition in the generator by fusible means exterior of the reservoir, the fusing of said fusible means starting or setting the generator in operation, thus permitting the gas generating materials to mix with the resultant generating 20 25 30 35 40 45 50 55 60 65 70 75 80 85 90 95 100 105 110

area and providing yielding means to normally close the outlet, which means is automatically adjustable by the pressure within the reservoir and the force of the ejected stream to increase or decrease the area of the outlet in accordance with such pressures within the reservoir, said means also being adapted to diffuse the ejected stream laterally.

In the drawing accompanying and forming a part of this specification there is shown in sectional side elevation a fire extinguisher with an embodiment of my invention applied thereto.

In the drawing I have shown an embodiment of my invention in connection with a fire extinguisher in which there is provided a reservoir 1 of suitable material to contain the fire extinguishing liquid, the reservoir having a filler opening closed by a cap or plug 2 and a discharge outlet 3.

As stated, the liquid is forcibly ejected from the reservoir or tank by pressure, such as gas pressure, within the reservoir for which purpose there is provided a gas generator comprising a receptacle 4 to contain a gas generating material, such as hydrochloric or sulphuric acid, said receptacle being suspended from the top of the reservoir in line with an opening adapted to be closed by a removable cover 5, and the receptacle having an outlet 6 leading into the reservoir. A tubular member 7 to constitute a part of a second receptacle is suspended in the first receptacle by a flange 8 thereon engaging with an inwardly extending ledge 9 of a flange 10 on the top of the reservoir, and the other end of the tube is closed and secured in position by the cover 5, suitable packing, as at 11, being interposed between the flanges 9 and 8 and the cover. By this construction the tubular member 7 may be readily removed for cleaning or the supplying of the gas generating material to the receptacle 4.

To adapt said tubular member as a receptacle to carry another gas generating material, such as bicarbonate of soda, and maintain said material in the tubular member free from and permit the material to mix with the material in the receptacle 4 when required, the lower end of the tubular member 7 is closed by a movable member or bottom 12; that is, the bottom is adapted to be moved away from the tubular member 7 to permit the bicarbonate of soda to drop onto the acid in the receptacle 4 with the result-

In fire extinguishers of this type the area of the outlet of the reservoir is fixed and is such that the liquid may be readily and forcibly discharged therethrough from the reservoir by the gas pressure within the reservoir and diffused laterally by a head carried by the reservoir adjacent said outlet opening. The fire extinguishing liquid used in this type of extinguisher is carbon tetrachloride, or a composition of which carbon tetrachloride constitutes a component part, and the liquid is of such a nature that it will expand and volatilize at a relatively low temperature, say about 170 degrees, with the result that as the temperature of the atmosphere surrounding the extinguisher increases the liquid will expand within the reservoir. Should the discharge outlet of the reservoir be so proportioned as to permit of the discharge of the liquid by the gas pressure at constant volume or stream of predetermined size it will not be of sufficient size to permit of the ready discharge of the liquid as expansion of the liquid takes place in the reservoir with the result that the expansive force of the liquid in connection with the gas pressure will rupture the reservoir. It is the object of the present invention to overcome this disadvantage by making the reservoir outlet of considerable

ing reaction. This bottom 12 in the normal condition of the extinguisher is retained in position contiguous to the lower end of the tubular member 7 by a stem 13 connected 5 thereto extending through the receptacle 4 and through an opening in a plug 14 in the reservoir to the exterior of the latter, and retained in its normal position adjacent the member 7 by a fusible bar 15 consisting of a 10 pair of endwise abutting sections secured in such position by a fusible solder, as shown at 16, said bar being carried at its ends by a ring 17 having screw threaded connection with a collar 18 connected to the plug 14, and 15 upon which bar 15 the end of the rod 13 rests. Said rod 13 engages in a tube 19 secured to and closed at one end by the plug 14 and the rod is slidably mounted on the plug 14 and a disk 20 in the tube. The tube 20 extends up through the bottom of the receptacle 4 and up into an inwardly extending tubular portion 21 of the bottom. The rod 13 also extends up into the tubular bottom portion 21 and is connected at its upper end 25 to the closed end of said tubular portion and carries a valve 22 adjacent the end which is adapted to co-operate with a valve seat at the end of the tube 19 to shut off communication between the tube 19 and the receptacle 4 30 when the bottom 12 drops away from the receptacle 7 and the reaction of the gas generating materials is taking place.

The outlet 6 of the receptacle 4 to the reservoir is sealed to normally prevent access 35 to the fire extinguishing liquid into the said receptacle as well as prevent evaporation of the acid. For this purpose I provide a leaf 24 of fragile material which will be readily ruptured or punctured by the gas pressure 40 in the receptacle 4, a tin foil leaf having been found to answer the purpose. To secure this leaf to the outlet it is secured to a washer 24, which washer is clamped to the end of a tube 27 in which the outlet is located by a 45 perforated cap 26.

To discharge the liquid from the reservoir there is connected to a tubular member 28 in which the outlet 3 is located, a tube 29 extending to adjacent the top of the reservoir 50 and then bent reversely and extending to adjacent the bottom. This tube and the outlet is of relatively large size, and the outlet is closed by a valve 30 co-operating with a valve seat in the outer end of the member 28. 55 This valve is slidably mounted on a stem 31 fixed at one end in the outlet member 28 and the valve is maintained in yielding engagement with the valve seat by a spring 32 coiled about the stem 31 and confined between the valve and lock nuts 33 on the outer end of the stem. It will thus be obvious that the valve is automatically adjustable to regulate the discharge outlet in accordance with the pressure in the reservoir and the force of 60 the ejected stream. The valve is preferably 65

in the form of what is commonly termed "a sprinkler head" to diffuse the ejected liquid laterally, and for which purpose it is bevelled or cone-shaped, the cone face being extended to increase the deflecting surface 70 thereof. It will be understood that the force with which the valve engages with the seat may be increased or decreased by adjusting the lock nuts on the valve stem.

In operation the reservoir is first filled 75 with the liquid. The leaf closure 24 is then applied to the outlet 5 of the receptacle 4 and the acid supplied to said receptacle. The bottom 12 and the tubular member 7 are then inserted through the cover opening into 80 the receptacle 4 and the bottom adjusted through the fusible bar 15 to lie contiguous to the lower end of the tubular member 7 when the bicarbonate of soda is supplied to the thus formed receptacle and the cover 5 85 secured in place. The extinguisher in this condition is suspended or supported in a suitable position as from the ceiling or an opening therein. When a fire occurs and the temperature of the atmosphere surrounding the extinguisher attains a predetermined degree the fusible solder 16 will melt or fuse, the bar sections separating at the abutting ends and the rod 13 will drop and with it the bottom 12 of the receptacle, 90 the soda mixing with the acid, generating gas and the pressure of the gas in the receptacle 4 rupturing the seal 24 and passing into the reservoir where such gas pressure acting on the liquid in the reservoir will eject the 100 liquid through the tube 29, the force and pressure of the liquid unseating the valve 30 against the action of the spring 32, and the reacting liquid impinging against the bevelled surface of the valve will be diffused 105 laterally. It will be readily understood that the movement of the valve away from the outlet 3 to increase or decrease the area of said outlet will be regulated automatically 110 in accordance with the pressure within the reservoir and the force of the ejected stream, and that no matter what the volume of the ejected stream may be it will be diffused laterally by the bevelled face of the valve.

Having thus described my invention, I 115 claim:

1. In a fire extinguisher, the combination of a reservoir for a fire extinguishing liquid having a discharge outlet with a valve seat; a generator in which to generate gas in the 120 reservoir having an outlet leading into the reservoir; a fragile leaf to close said outlet adapted to be ruptured by the pressure within the generator; a slidably supported valve exterior of the reservoir to close the reservoir outlet; and a spring to normally urge the valve to its seat to close the valve, said valve being operable by the liquid through the pressure in the reservoir to open the outlet and vary the area of the outlet opening, 125 130

and adapted to diffuse the discharged liquid laterally.

2. In a fire extinguisher, the combination of a reservoir for a fire extinguishing liquid having a discharge outlet; a generator in the reservoir having an outlet leading into the reservoir and means to maintain gas generating materials therein in a separated condition, said means having a part to extend to the exterior of the reservoir; fusible means to co-operate with said projecting means to normally maintain said means in position with the gas generating materials in a separated condition in the generator and the fusing of said fusible means causing said means to operate and the gas generating materials to mix; a slidably supported valve for the reservoir outlet; and yielding means to normally maintain the valve in closed position, said valve being operable to open the outlet by the liquid through the gas pressure in the reservoir, and to vary the outlet opening in accordance with the pressure within the reservoir for the purpose specified.
3. In a fire extinguisher, the combination of a reservoir for a fire extinguishing liquid having a discharge outlet; a generator in said reservoir having an outlet leading into the reservoir; means in the generator to normally maintain gas generating materials in a separated condition in the generator and operable to permit the materials to mix, said means having a stem projecting to the exterior of the reservoir; a fusible bar cooperating with the projecting stem to maintain said means in position with the materials in the generator in a separated condition, the fusing of said bar permitting said means to operate to cause the materials to mix; a slidably supported valve for the reservoir outlet; and a spring to yieldingly maintain said valve in closed position; said valve being operable from the pressure within the reservoir to open the reservoir outlet and vary the area of said outlet opening in accordance with the pressure within the reservoir and adapted to diffuse the discharging liquid for the purpose specified.

GEO. T. PEARSONS.
